UNITED STATES PATENT OFFICE.

THOMAS J. MURDOCK, OF FRANKLIN, MASSACHUSETTS, ASSIGNOR TO MURDOCK AND GEB COMPANY, OF FRANKLIN, MASSACHUSETTS.

BOBBIN-HOLDER.

No. 860,933.

Specification of Letters Patent.

Patented July 23, 1907.

Application filed April 16, 1905. Serial No. 255,730.

To all whom it may concern:

Be it known that I, THOMAS J. MURDOCK, a citizen of the United States, residing at Franklin, in the county of Norfolk and State of Massachusetts, have invented a new and useful Improvement in Bobbin-Holders, of which the following is a specification.

This invention has reference to an improvement in bobbin holders used for frictionally securing bobbins to the spindles of mules or other spinning machines.

10 In bobbin holders as heretofore constructed the coiled spring for holding the jaws in the closed position on the head of the bobbin is placed above the pivot of the jaws. In practice this has been found to be detrimental for as the spindle gained in speed the centrifugal 15 force would tend to open the jaws and spring and loosen or release the bobbin.

The object of my invention is to improve the construction of bobbin holders, whereby the lower ends of the jaws of the holder are over-weighted and the springs 20 for holding the jaws in the closed position are placed below the pivot of the jaws.

A further object of my invention is to simplify the construction of bobbin holders, thereby reducing the cost of manufacturing the same.

25 My invention consists in the peculiar and novel construction of a bobbin holder having a plurality of over-weighted jaws, springs placed below the pivot of the jaws adapted to engage with the over-weighted lower end of the jaws and hold the jaws in the closed position under spring tension, and other details of construction, as will be more fully set forth hereinafter.

Figure 1 is a side view of a mule spindle, showing a bobbin frictionally secured to the spindle by my improved bobbin holder. Fig. 2 is a top view of the holder with the bobbin removed from the holder. Fig. 3 is a view of the holder looking at the underside of the same. Fig. 4 is a vertical sectional view taken on line X X of Fig. 3 through the head of the bobbin and the holder. Fig. 5 is an enlarged detail view of part of the holder frame, showing one of the openings for the clamping jaws. Fig. 6 is an enlarged detail sectional view through the holder frame taken on line Y Y of Fig. 5, and Fig. 7 is an enlarged detail sectional view of part of a clamping jaw and the end of a spring, showing the 45 means of attaching the end of the spring to the lower over-weighted end of the jaw.

In the drawings, *a* indicates a spindle, and *b* a bobbin having the circular head *b'* and the usual central hole for the spindle.

50 My improved bobbin holder consists of a circular frame *c* having the downwardly-turned annular lip *c'*, the central hole *c''* and the curved openings *c³ c³* in the top of the frame adjacent the edge. These openings *c³ c³* are shaped to receive the clamping jaws of the 55 holder. From the inner edges of the openings *c³ c³*

tongues *c⁴* of the metal extend toward the center of the said openings. These tongues are flexible and may be bent substantially at right angles to the body of the circular frame. In Figs. 5 and 6 the tongues are shown in full lines in their flat or normal position, that is bent 60 down, and in dotted lines in their bent up position. The tongues are bent up and the clamping jaws are inserted in the openings *c³ c³* and the tongues *c⁴ c⁴* are then bent down to hold the clamping jaws in their operative position in the frame. A collar *c⁵* having the end 65 *c⁶* reduced in size to form a shoulder is secured to the frame *c* by passing the end *c⁶* through the central hole *c''* in the frame and upsetting the end *c⁶* onto the frame, as shown in Fig. 4. Each of the clamping jaws *d d* are constructed to have the outwardly-curved upper end 70 *d'*, the inwardly and downwardly bent central portion forming the shoulder *d²* and the enlarged over-weighted lower end *d³* on the inner side of which are raised circular lips forming the depressions *d⁴ d⁴*, as shown in Fig. 7. These depressions are made by first stamping 75 up from the outside a cup-shaped depression and then stamping the bottom of the cup shaped depression back from the inside. The clamping jaws *d d* are also shaped to conform to the circular frame *c*, as shown in Figs. 2 and 3. The curved wire springs *e e* each have the outwardly-bent ends *e' e'*, as shown in Fig. 7.

In assembling my improved bobbin holder the clamping jaws *d d* are inserted upward through the openings *c³ c³* in the frame *c* and the tongues *c⁴ c⁴* bent down to pivotally secure the jaws in the frame. The wire 85 springs are now placed into position by contracting the spring and snapping the ends *e' e'* of the springs into the depressions *d⁴ d⁴* in the lower ends of the locking jaws. One end of a spring enters a depression in a jaw and the other end enters a depression in the adjacent 90 jaw, as shown in Fig. 3, thus bringing the springs under the pivot of the jaws. The holder is now secured by forcing the collar *c⁵* onto the spindle, as shown in Fig. 4.

By this construction and arrangement of the parts the tension of the springs *e e* exerts an outward pressure 95 on the lower ends of the clamping jaws and an inward pressure on the upper ends of the jaws, thus firmly holding the bobbin on the spindle, and this tension of the springs is materially assisted by the over-weighted lower ends of the jaws when the spindle is running at 100 its maximum speed.

Having thus described my invention, I claim as new and desire to secure by Letters Patent;—

1. In a bobbin holder, a circular frame having a series of curved openings adjacent its periphery and a central hole, a collar secured to the frame in the central hole, a series of clamping jaws pivotally secured in the curved openings, means for exerting an expanding spring tension on the clamping jaws below the pivot of the jaws, and means for securing the holder to a spindle, as described. 105
2. In a bobbin holder, a circular frame having a series 110

- of curved openings adjacent its periphery and a central hole, a collar secured to the frame in the central hole, a series of clamping jaws having enlarged over-weighted lower ends in the inner face of which are depressions, 5 means for pivotally securing the clamping jaws in the curved openings in the frame, and means for exerting a spring tension on the lower ends of the jaws below the pivot of the same, consisting of curved wire springs the ends of which enter the depressions in adjacent jaws, as 10 described.
3. In a bobbin holder, the combination of a circular frame c having the downwardly-turned annular lip c' , the central hole c^2 , the curved openings c^3 c^3 adjacent the edge and the tongues c^4 c^4 on the inner edge of the openings 15 c^3 c^3 , a collar c^6 having the end c^6 secured in the central

hole c^2 by upsetting the end c^6 onto the frame, clamping jaws d d pivotally secured in the openings c^3 c^3 by the tongues c^4 c^4 each jaw having the outwardly-curved upper end d' , the shoulder d^2 , the enlarged over-weighted lower end d^3 on the inner side of which are the depressions d^4 d^4 , 2) and the curved wire springs e e each spring having the outwardly-bent ends e' e' adapted to enter the depressions d^4 d^4 in the jaws and exert a spring tension on the jaws below the pivot of the same, as described.

In testimony whereof I have signed my name to this 25 specification in the presence of two subscribing witnesses.

THOMAS J. MURDOCK.
